US0D1090676S

(12) **United States Design Patent** (10) Patent No.: **US D1,090,676 S**
(45) Date of Patent: ** Aug. 26, 2025

(54) **CAMERA**(71) Applicant: **GoPro, Inc.**, San Mateo, CA (US)(72) Inventors: **John George Muhlenkamp, IV**,
Mapleton, UT (US); **Huy Phuong
Nguyen**, Alpine, UT (US); **Daniel J.
Coster**, Oakura (NZ)(73) Assignee: **GoPro, Inc.**, San Mateo, CA (US)(***) Term: **15 Years**(21) Appl. No.: **29/930,423**(22) Filed: **Feb. 29, 2024**

(60) Division of application No. 29/892,363, filed on May 17, 2023, now Pat. No. Des. 1,024,165, which is a division of application No. 29/860,407, filed on Nov. 18, 2022, now Pat. No. Des. 997,232, which is a continuation of application No. 29/838,412, filed on May 12, 2022, now Pat. No. Des. 988,390, which is a division of application No. 29/814,777, filed on Nov. 9, 2021, now Pat. No. Des. 956,123, which is a division of application No. 29/785,302, filed on May 25, 2021, now Pat. No. Des. 950,629, which is a division of application No. 29/706,013, filed on Sep. 17, 2019, now Pat. No. Des. 920,419.

CLAIM

The ornamental design for a camera as shown and described.

DESCRIPTION

FIG. 1 is a top, front and left side perspective view of a camera showing our new design;

FIG. 2 is a bottom, rear and right side perspective view thereof;

FIG. 3 is a front view thereof;

FIG. 4 is a rear view thereof;

FIG. 5 is a right view thereof;
FIG. 6 is a left view thereof;
FIG. 7 is a top view thereof;
FIG. 8 is a bottom view thereof; and,
FIG. 9 is a cross-sectional view thereof, taken along line 9-9
of FIG. 8.

The equal length broken lines depict portions of the camera
that form no part of the claimed design. The dash-dot lines
denote the boundary of the claim and form no part of the
claimed design.
